H. ARRUGA

ILLUMINATING DEVICE

Filed July 24, 1924

Inventor:

Dr. Hermenildo Arruga

UNITED STATES PATENT OFFICE.

HERMENEGILDO ARRUGA, OF BARCELONA, SPAIN, ASSIGNOR TO CARL ZEISS, OF JENA, GERMANY.

ILLUMINATING DEVICE.

Application filed July 24, 1924. Serial No. 728,032.

To all whom it may concern:

Be it known that I, HERMENEGILDO ARRUGA, a citizen of Spain, and residing at Barcelona, Spain, have invented a new and useful Illuminating Device (for which I have filed an application in Germany August 2, 1923), of which the following is a specification.

The present invention relates to that kind of illuminating devices for an apparatus, destined for examining the eye, in which a diaphragm is disposed between a source of light and a collective lens system and whereby the latter serves for imaging the diaphragm into the interior of the eye to be examined. When using such an illuminating device only a small portion of the retina is illuminated at any one time and the observer is obliged to move the illuminated spot over the retina. This can be very easily effected in the lateral direction if the whole illuminating device be rotatable in a horizontal plane. In the height-direction, however, it is not easy to do this if (as it has already been carried out) the whole illuminating device can be tilted in a vertical plane. For, owing to the not inconsiderable bulk of such a device it is difficult to displace the illuminated spot quite gradually. According to the present invention an easy operation may be attained by rendering adjustable in the height direction the said collective lens system relatively to the carrier on which this system, the diaphragm and the source of light are disposed.

The annexed drawing shows a constructional example of the invention in a front elevation, partly in section.

On a base plate *a* rests a stand *b*, carrying at the top a rotatable nut *c*. A holder *d*, threaded at its bottom, is screwed into this nut. On the top of the holder *d* is fixed a casing *e* in which there are disposed a glow lamp *f*, a condenser system *g¹*, *g²* and a diaphragm *h*. On the holder *d* is further fixed an arm *i* which is provided at its free end with a carriage guide *j*. In this

guide a body *k* can be displaced. Through a vertical bore of this body is passed a bolt 50 *l* which has a slit *m*. Through the latter passes a pin *n* fixed in the body *k*, so that the pin is displaceable but not rotatable relatively to the body. At its top the bolt *l* carries a collective lens *o*; the lower part 55 of the bolt is threaded. A bushing *p* is rotatable upon the body *k*; it is supported by a collar *q* screwed to this body. With the bushing *p* is rigidly connected a capsule *r* provided with a female thread in which engages the thread of the bolt *l*.

When using the device the observer at first imparts to the holder *d* by rotating the nut *c* such a height that the eye to be examined can be struck by the light of the glow lamp. Thereupon the observer adjusts the body *k* on the carriage guide *j* to such a position that the diaphragm *h* is imaged by the lens *o* on the retina of the eye to be examined. If he desires to cause the illuminated spot to travel in the height-direction, he turns the capsule *r* in the one or the other direction. The observer will be able to cause the spot to travel in the lateral direction by carrying out with the whole upper part 75 slight rotations with which the holder *d* is guided in the thread of the nut *c*.

I claim:

In an illuminating device for an apparatus destined for examining the eye a holder, 80 of this holder being disposed a source of light, a condenser system and a diaphragm, the condenser system lying between the source of light and the diaphragm, an arm connected with the said holder, optical means, adapted to form a real image, an arm on which the said optical means are disposed, the diaphragm lying between the said condenser system and the said optical means and the latter being adapted to image 85 the diaphragm into the interior of the eye, and an adjusting device fitted to the arm and admitting of displacing the said optical means vertical relatively to the arm. 90

DR. HERMENEGILDO ARRUGA.
